US00D702245S

(12) **United States Design Patent**
Susman(10) **Patent No.:** **US D702,245 S**
(45) **Date of Patent:** **** Apr. 8, 2014**(54) **SCANNING FRAME**

(75) Inventor: **Victor Susman**, Kings Park, NY (US)
 (73) Assignee: **Victor Susman**, Kings Park, NY (US)
 (**) Term: **14 Years**
 (21) Appl. No.: **29/410,713**

(22) Filed: **Jan. 11, 2012**(51) LOC (10) Cl. **14-02**
 (52) U.S. Cl. **USPC ..... D14/453**(58) **Field of Classification Search**
 USPC D14/420-425, 453, 432, 439-441, 450,
 D14/356; D6/300-302; D19/86; 40/765;

Primary Examiner — Susan Moon Lee

(74) Attorney, Agent, or Firm — Limin Wen

(57) **CLAIM**

The ornamental design for the scanning frame, as shown and described.

DESCRIPTION

FIG. 1 is a front perspective view of a scanning frame showing my new design;

FIG. 2 is a front view thereof; and,

FIG. 3 is a back elevational view thereof.

The claimed scanning frame is used to hold photos or pictures and fix them on the surface of a scanner.

1 Claim, 3 Drawing Sheets(56)
